COMBINED SKEIN HOLDER AND BALL WINDER

Joseph R. Silvia, 1224 Center St.,
Middleboro, Mass. 02346

Filed Apr. 29, 1966, Ser. No. 2,071

Term of patent 7 years

(Cl. D3—19)

FIG. 1

FIG. 3

FIG. 1 is a combined skein holder and ball winder showing my new design;

FIG. 2 is an enlarged perspective view of the skein holding portion thereof as it appears removed from the base and in a folded position, and

FIG. 3 is an enlarged perspective view of the base portion of the design shown in FIG. 2 as it appears with the skein holding portion removed.

I claim:

The ornamental design for a combined skein holder and ball winder, substantially as shown and described.
